Primary Examiner — Susan Moon Lee(74) Attorney, Agent, or Firm — Justin Lampel(57) CLAIM

I claim the ornamental design for a dog food mat, as shown and described.

DESCRIPTION

FIG. 1 is a perspective view of a dog food mat showing the claimed design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof; and,

FIG. 7 is a left side view thereof.
